CLAIM

The ornamental design for a handheld device for holding plastic grocery bags, as shown and described.

DESCRIPTION

FIG. 1 is a front perspective view of a handheld device for holding plastic grocery bags showing my new design; FIG. 2 is a front perspective on an enlarged scale thereof; FIG. 3 is a front elevational view thereof, the rear elevational view being the mirror image thereof; FIG. 4 is a top plan view thereof;

FIG. 5 is a bottom plan view thereof; and,

FIG. 6 is a left side elevational view, the right side elevational view being the mirror image thereof.

The dotted line showing of a hand and portions of the handles of a plastic grocery bag in FIG. 1 are for information only and form no part of the claimed design.
